UNITED STATES PATENT OFFICE.

WILLIAM McCONWAY, JR., OF PITTSBURGH, PENNSYLVANIA, ASSIGNOR TO THE
McCONWAY & TORLEY COMPANY, OF PITTSBURGH, PENNSYLVANIA, A COR-
PORATION OF PENNSYLVANIA.

CAR-COUPING.

1,294,288.

Specification of Letters Patent.

Patented Feb. 11, 1919.

Application filed November 27, 1918. Serial No. 264,315.

To all whom it may concern:

Be it known that I, WILLIAM McCONWAY, Jr., a citizen of the United States, residing at Pittsburgh, in the county of Allegheny and State of Pennsylvania, have invented 5 certain new and useful Improvements in Car-Couplings; and I do hereby declare the following to be a full, clear, and exact description of the invention, such as will enable others skilled in the art to which it 10 appertains to make and use the same.

My invention relates to car couplers of the type in which the lock is supported in lock-set position by a horizontally rotatable lever 15 that serves to force the knuckle to open position. The best known example of this type of car coupler is the Master Car Builders' standard D coupler, and my invention is especially adapted to improve and perfect 20 such a coupler so as to render its operation reliable.

In the standard D coupler the lock at times fails to return to normal or locked position after the knuckle has been opened and 25 closed following the operation of locksetting. This defective operation is due to the knuckle opening lever moving into the path of locking movement of the lock in such manner as to prevent the lock from dropping to locked position. This defect, which 30 is an inherent consequence of the form and manner of combining the elements, is apt to be magnified in service, since the blows delivered to the knuckle opening lever by 35 the knuckle in closing cause or tend to cause a compression of the metal of the coupler head adjacent the knuckle opener, thereby permitting the arm of the knuckle opening lever that is nearer the lock to project correspondingly farther into the path traversed by the lock in executing a locking 40 movement.

It is the object of my invention to remedy this defect in a simple and efficient 45 manner. To this end the invention, generally stated, involves the combination of a coupler head, a knuckle pivotally mounted thereon, a horizontally rotatable knuckle opening lever pivotally mounted in the lower part of the coupler head and having 50 one arm extending behind the tail of the knuckle and the other arm arranged adjacent to and in the rear of the lock, a gravity actuated lock which normally restrains

opening of the knuckle and which is adapted to be supported in unlocked or lock set position on the adjacent arm of the knuckle opening lever, and a stop on the guard arm side of the coupler head transversely overlapping the said lock and knuckle opening 60 lever and serving as means for limiting the movement of the shorter arm of said lever toward the lock.

In the drawings, which show my invention as embodied in the Master Car Builders' standard D coupler,

Figure 1 is a horizontal sectional view of the mechanism, the knuckle and knuckle opener being in plan.

Fig. 2 is a vertical section, taken in the plane of the line 2—2, Fig. 1, the lock being in elevation.

Fig. 3 is a transverse sectional view, taken on the line 3—3, Fig. 1, the lock and knuckle opening lever being in elevation and the knuckle being omitted.

I will now proceed to describe my invention more fully so that others skilled in the art to which it appertains may apply the same.

The coupler head 1 has mounted thereon a rotatable knuckle 2, these parts being preferably connected by means of the usual knuckle pin 3. When in closed or coupled position the knuckle normally is restrained 85 from swinging outward by means of a lock 4 which extends in front of the tail of the knuckle. The lock 4 is provided with a downwardly extending portion or leg 5 which preferably is provided at its lower 90 end with an elongated slot or eye 6 adapted to receive a finger or trunnion 7 at the upper end of a lock lifter 8 forming a part of a well known type of underneath release rigging. In order to clear the stop 9 by 95 which the knuckle opening lever 10 is prevented from interfering with the locking operation of the lock 4, the trunnion 7 of the lock lifter 8 is inserted in the slot 6 of the lock from the knuckle side of the coupler and the width of the lower end of the lug 5 of the lock is reduced adjacent the slot 6. For a similar reason the trunnion 7 at the upper end of the lifter 8 is made of suitable length to pass the stop lug 9 when the lower end of the lock 4 swings rearwardly 105 in actuating the knuckle opening lever 10.

On the knuckle side of the lock opening

in the lower part of the coupler head 1 is a lock - to - the - lock projection 11 which is adapted to be engaged by the upper end of the lifter 8 when the lock 4 accidentally attempts to assume an unlocked position, the lock thus being prevented from jarring upward to a position permitting the knuckle to swing open. When, however, the lifter 8 is actuated to lift the lock 4 the trunnion 7 of 10 the lifter slides upwardly and rearwardly in the slot 9, thereby shifting the upper end of the lifter from its normal position beneath the projection 11 and allowing the lifter to raise the lock.

15 In locked position the lock 4 rests upon the upper surface of the shorter arm 12 of a horizontally rotatable knuckle opening lever 10 which is mounted in the lower part of the coupler head, the lock being formed with 20 a seat or shoulder 13 for that purpose. On the leg 5 of the lock is a lower shoulder or seat 14 which is adapted to be seated upon the shorter arm of the knuckle-opening lever 10 when the lock, upon being raised to unlocked position by the lifter 8, swings rearwardly under the influence of gravity. When the lock is thus supported in lockset position on the knuckle opening lever, the knuckle 2 may be rotated outwardly to open 25 position. The leg 5 of the lock is provided adjacent the guard-arm side of the coupler with a longitudinally extending guideway or recess 15 for receiving the stop lug 9.

The forward face of the lock 4 is provided 30 with a projection 16 which, when the lock is raised above unlocked position, engages and rocks upon a lug 17 formed on the interior of the forward upper portion of the coupler head 1, the leg 5 of the lock thus being 35 caused to execute a positive rearward movement which forces the shorter arm of the knuckle opening lever rearwardly and thereby causes the longer arm of the lever 10 to press against the rear face of the knuckle 40 tail and rotate the knuckle 2 to open position.

On the guard-arm side of the coupler head 1 is a short vertical rib 9 which is adapted to overlap the lock 4 and the shorter 45 arm 12 of the knuckle opening lever. This rib or stop 9, which operates in the longitudinally extending groove 15 in the leg 5 of the lock, limits the rotation of the shorter arm of the knuckle opening lever toward the lock 4 and prevents said arm from projecting into the path of movement traversed by the lock when the latter is returning to

locked position following a closed rotation of the knuckle.

I claim:

1. A car coupler having a head, a knuckle, a horizontally rotatable lever for opening said knuckle, a lock for said knuckle adapted to move toward one of the arms of said lever and to be supported on said arm in lockset position, and a stop on the guard-arm side of the coupler head transversely overlapping the said lock and lever and constituting means for limiting the movement of said lever arm toward said lock. 70

2. A car coupler having a head provided with a lock opening, a knuckle, a horizontally rotatable lever mounted in the lower part of said head for opening said knuckle, an upwardly movable and rearwardly swing- 75 ing lock adapted to be supported in lockset position on one of the arms of said lever, a stop on the guard-arm side of said coupler head for limiting the movement of said lever arm toward said lock, a lock lifter for actu- 80 ating said lock from beneath said coupler head, and a projection on the knuckle side of the lock opening of the coupler head adapted to be engaged by said lifter to there- 85 by prevent said lock from accidentally mov- ing to unlocked position.

3. A car coupler having a head, a knuckle, a horizontally rotatable lever for opening said knuckle, a lock for said knuckle adapted to be supported in lockset position on 90 one of the arms of said lever, and a stop on the guard-arm side of said coupler head for limiting the movement of said lever arm toward said lock, the lower portion of said lock being provided with a downwardly ex- 95 tends groove adapted to receive said stop.

4. A car coupler having a head, a knuckle, a horizontally rotatable lever for opening said knuckle, a lock for said knuckle adapted to be supported in lockset position on one 100 of the arms of said lever, a stop on the guard-arm side of the coupler head for limiting the movement of said lever arm toward said lock, and a lock lifter for actuating said lock from beneath said coupler head, 105 the lower end of said lock being provided with a slot and being laterally displaced with respect to said stop, and said lifter having at its upper end a trunnion insertible in said slot from the knuckle side of said coupler head. 110

In testimony whereof I affix my signature.

WILLIAM McCONWAY, JR.
